UNITED STATES PATENT OFFICE

CHARLES H. QUINN, OF SAN FRANCISCO, CALIFORNIA, ASSIGNOR TO THE STANDARD STOKER COMPANY, INCORPORATED, A CORPORATION OF DELAWARE

LOCOMOTIVE STOKER

Application filed October 18, 1928. Serial No. 313,233.

This invention relates to that type of stoker which conveys the fuel from the source of supply by a conveyor tube or conduit, the forward or delivery end of which extends into the boiler firebox or furnace and which is protected from the intense heat generated in the firebox by an auxiliary or protecting grate. More specifically, the invention particularly relates to improved means for securing the auxiliary or protecting grate in its proper position.

In stokers of this type the fuel is delivered to the firebox through a conduit, the forward end of which extends above the firebox grates and terminates in a discharge opening at a height above the grate from which the fuel emerging from the discharge opening can be scattered over the fire by suitable spreading means, such as steam jets. The discharge end of the conduit being thus exposed to the intense heat of the firebox, it is necessary to use some means for protecting it from the fire and for this purpose there is usually provided an auxiliary or protecting grate which is in the form of an upstanding perforated wall or skirt extending about the exposed end of the stoker conduit as is generally exemplified in the United States Letters Patent 1,606,182, granted to Frank P. Roesch, on date of November 19, 1926.

As clearly brought out in the aforesaid patent, steam locomotives to which this invention is especially applicable are constructed to permit the rear end of the boiler to move on the locomotive frame so as to provide for expansion and contraction of the boiler. When installing stokers of the character shown, to locomotive boilers, it is customary to secure the delivery or discharge conduit to the locomotive frame and apply the protecting grate about the upper end of the conduit in a manner adapted for it to move with the boiler without striking or displacing the stoker conduit. The space between the stoker conduit and the protecting grate is covered at the top and opens downwardly into the ash pan or to the atmosphere which space provides for the passage of air around the stoker conduit and into the combustion chamber through the perfora-

tions in the protecting grate, and thus the protecting grate prevents the flame from coming into contact with the stoker conduit and the passage of air through the perforated wall prevents overheating of the conduit and also of the protecting grate.

It is ordinary practice to mount the protecting grate in position within the firebox on the grate center bearer or bar and providing depending lugs from the protecting grate which are intended to prevent slippage of the protecting grate and hold it closely to the backwall of the firebox. While the manufacturer of the stoker constructs the stoking device and the protecting grate in accordance with the locomotive specifications it is common practice to find that the protecting grate does not fit closely to the backwall of the firebox or that the depending lugs are not in proper position to prevent forward or sidewise slipping motion of the protecting grate which results in the formation of large gaps or spaces, which offering the path of least resistance to the inflowing air will permit the air to enter the firebox through the large gaps or spaces instead of through the perforated openings in the protecting grate which has the effect of permitting the heat of the fire to burn away the same destroying its value and in time damaging the stoker.

The present invention has for its object to overcome the objectionable features of prior construction by providing improved detachable and secure means for maintaining the protecting grate in proper position to provide for the positive circulation of air therethrough.

On the drawings,

Fig. 1 is a fragmentary central longitudinal vertical section through the rear portion of a boiler firebox with a stoker applied thereto; and

Fig. 2 is a detail plan section on the line 2-2 of Figure 1 looking in the direction of the arrows.

For the purpose of best illustrating the invention, it is shown on the drawings and will be described as used with a locomotive but it will be recognized that it can be used to

good advantage with other types of boiler stoker installations.

Referring descriptively to the drawings, the rear portion of a locomotive firebox 10 has a hollow backwall or backhead 11 comprising inner and outer sheets 12 and 13, respectively, the hollow portion being closed at its bottom end by a mud ring 14 to which the sheets 12 and 13 are secured. Within the firebox 10 is located the center bearer or bar 15 of the firebox grate structure which is generally adapted to pivotally support the usual firebox grates, which while not being shown are mounted in horizontal alignment with the center bar. This bar is forked at its rear end to form a flattened U-shaped opening 16 central of the rear portion of the firebox.

The stoker conveyor tube or conduit 17 which extends forwardly from the tender 20 under the locomotive cab deck 18, has an upper extending portion 19 at its forward end which extends into the firebox through the opening 16 to a point above the level of the fire to be maintained, and terminates in a discharge or delivery opening 20. Fuel is conveyed through the conduit 17 and forced upwardly through the portion 19 by a screw conveyor 21. As the fuel emerges from the discharge opening 20 it is projected and scattered over the firebed by a suitable steam blast discharged from the distributor head 22. The stoker conveyor conduit 17 is fixedly mounted to the locomotive frame 23 by the bracket 24.

Partially surrounding the upper end portion 19 of the stoker conduit is an auxiliary or protecting grate indicated as a whole at 25 which in the preferred form of construction comprises four cast metal sections 26, 27, 28 and 29, all of which are spaced from the conduit 19 and form a corresponding chamber or opening 30 with the opening 16 of the center bar 15. Sections 26 and 28 of the protecting grate forming right and left hand sections respectively, are supported on the forked portion of the bar 15, each section being provided at the lower edge with depending lugs as at 31 which lugs are intended to assist in maintaining each section in position on the bar 15. The upper sections 27 and 29 rest on the top of sections 26 and 28 and each section is formed with lugs 32 similar to lugs 31 for the purpose of preventing movement of the top sections on the lower sections 26 and 28. The side walls of the protecting grate sections extend rearwardly to the inside sheet 12 of the backhead and are closely fitted and held thereto by a novel securing means in which this invention resides as hereinafter described.

On the inner face of each of the forward transverse walls of the lower grate sections 26 and 28 is provided rearwardly extending lugs 33, 33a, each of said lugs having an opening therethrough as at 34, 34a, which

openings are adapted to receive the hook portion 35 of a securing bolt 36, as shown there are two such bolts provided, one on either side of the stoker conduit portion 19.

The main body of the bolt 36, the opposite end of which from the hook portion is threaded, extends rearwardly and projects through a nipple 37 or 37a of the backhead 11. The nipple or sleeve 37, 37a has its ends rolled or beaded over for sealed engagement with the inner and outer sheets of the backhead to form a passage through the backhead for the securing bolt 36, one nipple or sleeve being employed with each bolt. Mounted over the threaded end of each of the bolts 36 is a washer or bearing plate 38 of such diameter that a portion of it bears on the beaded portion of the nipple against the outside sheet 13 of the backwall 11. Locking nuts as at 39 are in threaded engagement with the threaded end of the bolt 36, and may be adjusted to bear against the bearing plate to cause the bolt 36 to tightly hold the protecting grate sections against the inner sheet 12 of the backhead.

All of the grate sections are formed with openings 40 which serve to permit the air from the chamber 30 and opening 16 to flow into the combustion chamber, thus assisting in the complete combustion of the fuel and serving to cool the conduit 19 and the protecting grate sections. The protecting grate may be made of one part or as many sections as desirable or any form of cooling wall may be used for the purpose described, and held in proper position by the securing means of this invention.

From the above construction it will be seen that the securing hook bolts, while being detachable, serve to hold the protecting grate in proper relation with the firebox backwall at all times regardless of the expansion or contraction of the boiler or its parts, and therefore insures the positive circulation of the cooling air, thus increases the life of the parts.

I claim:

1. In a locomotive stoker, the combination comprising a firebox backhead, a furnace grate extending forwardly from the backhead, a conduit extending upward into the firebox and having its delivery end at a point above said grate, a protecting grate partially surrounding the delivery end of said conduit in spaced relation therewith, and attachment means extending through the firebox backhead for securing said protecting grate thereto.

2. In a locomotive stoker, the combination comprising a firebox backhead, a furnace grate extending forwardly from the backhead, a conduit extending upward into the firebox and having its delivery end at a point above said grate, a protecting grate partially surrounding the delivery end of

said conduit in spaced relation therewith, and adjustable attachment means extending through the firebox backhead for detachably securing said protecting grate thereto.

5. 3. In a locomotive stoker, the combination comprising a firebox backhead, a furnace grate extending forwardly from the backhead, a conduit extending upward into the firebox and having its delivery end at a point above said grate, a protecting grate having an open end, said protecting grate partially surrounding the delivery end of said conduit in spaced relation therewith and having its open end in contact with the backhead, and bolts engaging said protecting grate and extending through the backhead for securing the protecting grate thereto.

20. 4. In a locomotive stoker, the combination comprising a firebox backhead, a furnace grate extending forwardly from the backhead, a fuel conduit extending upward into the firebox and having its delivery end at a point above said grate, an upstanding substantially U-shaped protecting wall within the firebox partially surrounding the delivery end of the conduit and in spaced relation therewith and having its open end in contact with the backhead, said protecting wall comprising sections separable on a vertical plane and bolts engaging each of said sections and extending through the backhead for securing said sections thereto.

25. 5. In a locomotive stoker, the combination comprising a hollow firebox backhead formed by inner and outer sheets, a furnace grate extending forwardly from the backhead, a fuel conduit extending upward into the firebox and having its delivery end at a point above said grate thereof, an upstanding substantially U-shaped protecting grate partially surrounding the delivery end of the conduit and in spaced relation therewith and having its open end in contact with the inner sheet of said hollow backhead, means for securing the open end of said protecting grate in contact with said inner sheet, said securing means comprising a plurality of lugs extending from the inner face of said protecting grate, each being adapted to receive one end of a respective securing bolt, a plurality of bolts each having a hook portion engaging one of said lugs, the body portion of each bolt extending rearwardly through a respective sleeve in said hollow backhead and means cooperating with the body portion for securing said bolt in adjustable locking engagement with the outer sheet of said backhead.

30. 6. In a locomotive stoker, the combination comprising a hollow firebox backhead formed by inner and outer sheets, a furnace grate extending forwardly from the backhead, a fuel conduit extending upward into the firebox and having its delivery end at a point above the grate thereof, a perforated

upstanding substantially U-shaped protecting grate partially surrounding the delivery end of the conduit and in spaced relation therewith, said protecting grate comprising sections separable on a vertical plane and attachment means extending through the firebox backhead detachably securing each of said sections thereto.

In testimony whereof I affix my signature.
